VESSEL COVER

Harry L. Pollock, Wilkinsburg, Pa.

Application May 17, 1934, Serial No. 726,181

4 Claims. (Cl. 53—8)

This invention relates to covers for culinary vessels of the type in which a portion of the cover is constructed so that liquid may be drained from the vessel and wherein an auxiliary cover is provided for closing the drainage portion.

One object of the invention is to provide such a cover with means for holding the auxiliary cover in tight fitting engagement with the main cover to close the drainage area.

Another object of the invention is to provide means for holding the auxiliary cover in position above the drainage area when it is raised therefrom.

These and other objects as may hereinafter appear are attained by the devices illustrated in the accompanying drawing in which,

Fig. 1 is a plan view of the cover embodying the invention.

Fig. 2 is an enlarged sectional view on the line 2—2 of Fig. 1 showing the auxiliary cover in closed position on the main cover.

Fig. 3 is a sectional view on an enlarged scale showing the auxiliary cover held in raised position.

Referring to the drawing wherein similar parts in the several views are designated by similar numerals, 10 indicates the main cover which may be of any desired contour but as shown is preferably constructed with a wide rim 11 so as to enable the cover to be used on vessels of varying diameters. Adjacent the rim 11 and connected thereto by an upstanding portion 12 is an annular depressed portion 13. Located in the depressed portion 13 and the upturned portion 12 within a confined area are a series of apertures 14 through which liquid may be drained. It is essential in the construction of the cover that the upstanding portion 12 be provided with apertures for when a vessel is tilted in order to drain off a liquid, the apertures in the upstanding portion 12 aid in carrying off any liquid which otherwise would be held in the depressed portion 13.

At 15 I have shown an auxiliary cover which is adapted to fit the depressed portion 13 and is sufficiently large to cover the apertured area. Normally the auxiliary cover 15 will lie on the main cover 10 and close the apertured area, however I will later describe a means for retaining the auxiliary cover in tight fitting engagement with the main cover.

The cover 15 is hingedly connected to the main cover 10 at a point interiorly of the apertured area. As a preferred means of connecting the covers I utilize a hinge joint shown generally at 17 which comprises the leaves 18 and 19 con-

nected by a pintle 24. The hinge leaf 18 is connected to the main cover 10 and the leaf 19 is connected to the auxiliary cover 15 by any suitable means. The free end of the leaf 18 is bent so as to form a hook 20, the function of which will later be brought out.

In order to hold the auxiliary cover 15 in raised position when it is desired to use the cover as a drainer, I have provided a spring member 21. In the embodiment disclosed the member 21 comprises a wire bent into rectangular shape and further bent into a substantial U shape with a coiled portion 25 midway between its ends to give resiliency. Other modifications of the member 21 may obviously be used, the essential feature being that it have a bowed or substantial U shape.

The spring member 21 is pivotally attached to the hinge leaf 19 at 22. When it is desired to hold the cover 15 in raised position, the free end 23 of the spring 21 is held by the hook portion 20 of the spring leaf 18.

The pintle 24 of the hinge joint hereinbefore referred to, has another function. The pintle 24 comprises a wire bent into the form of a bail the free ends of which are inserted into the joint of the hinge, and function as the hinge pintle.

The loop portion of the member 24 encloses the U shaped spring member 21 when the cover 15 is in closed position and may be pressed against the spring 21 to hold the cover 15 in tight engagement with the main cover 10, as best shown in Fig. 2. When it is desired to raise the auxiliary cover 15, the member 24 may be thrown back over the spring 21 to the position as shown in Fig. 3 so that the spring member 21 is free to pivot.

Having thus explained the several parts and operation of my invention, what I claim as new and desire to secure by Letters Patent is:

1. The combination of a cover for culinary vessels having a perforated area adjacent its edge, of an auxiliary cover for normally closing the perforated area, a hinge joint, one leaf of the hinge being fixed to the main cover and its free end being bent to provide a hook, the other leaf of the hinge being fixed to the auxiliary cover, a spring member having one end pivotally connected to one leaf of the hinge joint and its other end being free and adapted to be held by the hook on the other leaf of the hinge joint when the auxiliary cover is in raised position.

2. The combination of a cover for culinary vessels having a perforated area adjacent its edge, of an auxiliary cover for normally closing the perforated area, a hinge joint, one leaf of the

- hinge being fixed to the main cover and its free end being bent to provide a hook, the other leaf of the hinge being fixed to the auxiliary cover, a substantially U shaped spring member having 5 one end pivotally connected to one leaf of the hinge joint and its other end being free and adapted to be held by the hook on the other leaf of the hinge joint when the auxiliary cover is in raised position.
- 10 3. The combination of a cover for culinary vessels having a perforated area adjacent its edge, of an auxiliary cover for normally closing the perforated area, a hinge joint connecting the said covers, a substantially U shaped spring member having one end pivotally connected to one leaf of the hinge, the pintle of the hinge comprising a wire bent into the form of a bail and adapted to press against the U shaped spring
- 15

member and hold the auxiliary cover tightly against the perforated area in the main cover.

4. In a cover for culinary vessels, the combination of a main cover and an auxiliary cover, the main cover being provided with a perforated area 5 adjacent its edge, the auxiliary cover being hingedly connected with the main cover and adapted to normally close the perforated area in the main cover, a substantially U shaped spring member having one end pivotally connected to the auxiliary cover, a second spring member 10 forming the pintle of the hinge connection between the said covers and adapted to cooperate with the U shaped spring member to hold the auxiliary cover in close fitting engagement with the main cover.
